UNITED STATES PATENT OFFICE.

FRANK WILLIS EVELAND, OF HOT SPRINGS, ARKANSAS.

BURNER.

1,188,920.

Specification of Letters Patent. Patented June 27, 1916.

Application filed October 7, 1915. Serial No. 54,654.

To all whom it may concern:

Be it known that I, FRANK W. EVELAND, a citizen of the United States, and resident of Hot Springs, in the county of Garland and State of Arkansas, have invented certain new and useful Improvements in Burners, of which the following is a specification.

This invention relates to oil burners and is an improvement of the burner shown and described in Patent No. 1,099,542 issued to me on June 9, 1914, and consists in certain novel constructions, combinations and arrangements of parts differing from my patent which will hereinafter be described and claimed.

Among the objects of my invention is to provide an oil burner so constructed that the retort will be automatically cleaned during its operation.

Another object of my invention is to provide means whereby any residue collected in the burner when heating up and cooling off is automatically eliminated therefrom.

Another object is to provide a burner tip that is self-cleaning.

Still another object is to so locate and limit the reservoirs of the primary generator that generation of gas will start quickly and effectively.

Other objects will appear in the following detailed description of my device.

In the drawings which constitute a part of the specification, and in which the same reference numerals apply to the same parts throughout:—Figure 1 is a side elevation of my improved burner, part of one air chamber being shown in section. Fig. 2 is a top plan view of my burner. Fig. 3 is a top plan view of the damper mechanism. Fig. 4 is a section on line 4—4 of Fig. 2, and Fig. 5 is a broken horizontal sectional view through the retort portion of my burner.

The practical embodiment of my invention consists of a damper base 1 provided with holes 2 for securing it in position. On base 1 are formed air chambers 3 in the form of frusto-cones having circular notches 4 positioned in their upper portions and symmetrically disposed with respect to the longitudinal axis of said base. The purpose of these notches will appear hereinafter. Near each end and in the center of said base are formed holes 5 whose object will appear later. In the bottom portions of said air chambers are dampers 6 and 7 mounted on rods 8 and 9 respectively. Said rods 8 and 9

are turned up to form lever arms as indicated at 10 and 11 respectively. To said lever arms 10 and 11 are journaled links 12 and 13 which links at their other ends are journaled to lever arms 14 and 15 formed on damper rods 16 and 17 respectively. Said damper rods are journaled in bearing clips secured to said base plate at 18, 19, and 20, 21, respectively, and are provided at their outer ends with actuating means here shown as members 22 and 23, but it is obvious that other actuating means such as crosses or wheels, may equally well be used.

Supported directly over openings 5 are T's 24 and 25, and generator pipe 26, all provided with clean out plugs which are accessible through the openings 5 of the base plate 1. The T's 24 and 25 bear burner arms 27 and 28, respectively, which rest in the notches 4 of the air chambers hereinbefore described. Said burner arms bear the burners 29 and 30 and position them centrally over their respective air cones. Generator pipe 26 is directly connected with the central or generating retort 31 (see Fig. 5) and bears the burner 32 and cleanout plug 33. Retort 31 bears the generating reservoirs 34 and 35 positioned substantially over the generator burner. Said retort 31 is integrally formed and in open communication with the circular burner retorts 36 and 37 which in turn are supported by and are in direct communication with T's 24 and 25 respectively. Extending upward from circular retort 36 is a quarter turn 38 bearing the baffle arm 39 parallel with the longitudinal axis of the base plate. This baffle arm carries the baffle plate 40 adjustably secured thereto as indicated at 41. Central retort 31 is supplied with fuel through pipes 42, 43, and 44 provided at their outer ends with needle valves 45, 46, and 47 respectively, which control the oil supplied through pipe 48 from a tank not shown. Fuel pipe 44 carries a baffle-plate 49 centrally located over burner 30 and adjustably secured to said pipe as indicated at 50. The burner tips are all provided with sloping walls 51 as shown in Fig. 4 which tends to prevent carbon deposit thus insuring clean open burners at all times.

The manner of using my improved oil burner is as follows: Oil is supplied to generator burner 32 through supply pipe 42, central retort 31 and generator pipe 26. The heated gases from burner 32 quickly

causes reservoirs 34 and 35 to become red hot. When this condition is reached needle valves 46 and 47 are opened and the oil therefrom flows through pipes 43 and 44 5 and drops into the red hot reservoirs. Upon coming into contact with these red hot members the oil is immediately gasified and forced around the circular retorts 36 and 37 to burners 29 and 30. The gas is generated 10 so rapidly that it carries any carbon deposit in the retorts to the burners where it is incandescent and burned. When the burner cools off, condensation of the gasified oil takes place. This condensation settles in the bottom of T's 24 and 25. Some unconsumed carbon may from time to time 15 form in relatively large particles in the retorts this is carried by the blast of gas flowing to the burner and settles in this oil 20 where it is emulsified. When the burner gets heated up this oil is gasified and as these carbon particles become finely divided due to the emulsive action of the oil they are carried out by the currents of gas as fine 25 dust. Thus it is seen my retort burner is substantially self-cleaning.

Dampers 6 and 7 are capable of adjustment to control the supply of air to a nicely so that complete combustion is insured under all variations of atmospheric conditions.

I claim:—

1. A device of the character described comprising a base provided with openings and having frusto-conical air chambers having seat-forming notches in their walls and integral with said base and extending upwardly therefrom, manually controlled dampers mounted in said chambers, a centrally disposed initial generator, valve-controlled 35 oil supply pipes in communication with said generator, a generator pipe depending from and in communication with said generator, a burner on said pipe, generator reservoirs depending from said generator and in open 40 communication therewith, said reservoirs being positioned over the burner on said generator pipe, circular generator retorts extending horizontally from said central generator and in open communication there- 45 with, burner T's depending from that portion 50 of said retorts diametrically opposite said

generator and in open communication with said retorts, said T's being provided with clean-outs resting in the openings in said base, burner arms projecting from said T's 55 and resting in the notches in said chambers, burners provided with sloping under walls mounted on said arms, baffle-arms positioned over said burners and baffles mounted thereon. 60

2. A device of the character described comprising a base, said base having air chambers integral therewith having seat notches formed in their walls, manually controlled dampers mounted in said chambers, 65 an initial generator, valve controlled oil supply pipes in open communication therewith, a generator pipe depending from and in open communication with said generator, a burner mounted on said generator pipe, 70 generator reservoirs depending from and in open communication with said generator, generator retorts extending horizontally from said generator, burner supporting members joined to and in open communication 75 with said retorts and resting in said notches, burners on said members and baffles mounted over said burners.

3. A device of the character described comprising a base, members providing air 80 chambers on said base, dampers in said chambers, an initial generator mounted on said base, an initial generator burner, valve controlled means for supplying oil thereto, reservoirs depending from said generator 85 over said burner, valve controlled means for supplying oil to said reservoirs, main burners in said chambers, and retorts in open communication with said generator and said burners. 90

4. A device of the character described comprising a base, damper controlled means thereon for supplying air, an initial generator, a burner therefor, generating reservoirs depending from said generator substantially over said burner, valve controlled supplies of oil to said burner and reservoirs, retorts in open communication with said generator and burners in communication with said retorts centrally located over each 100 of said damper controlled means.

FRANK WILLIS EVELAND.
